THOMAS E. GRIFFITH AND LEE L. DODDS, OF CLEVELAND, OHIO, ASSIGNORS TO THE
W. S. TYLER COMPANY, OF CLEVELAND, OHIO, A CORPORATION OF OHIO.

SWITCH MECHANISM.

Application filed March 5, 1923. Serial No. 623,057.

The present invention, relating, as indicated, to switch mechanism, is more particularly directed to an improved type of quick-opening switch for use in connection with elevator doors. It is desirable to provide means in connection with elevator enclosure doors for breaking the operating circuit for the car as soon as the doors of the enclosure are open and for maintaining the circuit open as long as the doors are open. The present invention is directed to an improved type of switch for this purpose. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a front elevation showing an elevator enclosure, the doors therefor and our improved switch mechanism; Fig. 2 is a vertical central section through the switch mechanism looking at the same from the rear of Fig. 1; Fig. 3 is a similar view showing the switch member in a different position; Fig. 4 is a section on the line 4—4 of Fig. 2; Fig. 5 is a section on the line 5—5 of Fig. 2; Fig. 6 is a similar view, but showing the plunger element of the switch in its raised position; and Fig. 7 is a side elevation of the element shown in Fig. 6.

Referring now to Fig. 1, there is shown an elevator enclosure 1, provided with a door 2, locking means 3 and latch 4 therefor, and a carriage 5 from which the door is suspended and which moves with the door to the left during opening.

Mounted at the top of the enclosure 1 is a switch member 6 in the form of a hollow casing 7, in which is reciprocably mounted a plunger 8 carrying a roller 9 at its lower end and sliding through a cylindrical member 10 which acts as a guide for the plunger 8, and also as a support for electrical conducting wires 11 and 12, which pass into the casing through openings 13 and 14, respectively, therein. These wires are secured to binding posts 15 and 16, which pass through, and are in electrical contact with, metal strips 17 and 18, which are mounted on the

member 10 which is of insulating material. Extending from the strips 17 and 18 are contact fingers 19 and 20, respectively, which extend downwardly from the block 10 and into position to be contacted by means of a metal disk 25 carried on a cylindrical fiber disk 26, which is freely movable on the plunger 8. The circuit is closed through the resilient fingers 19 and 20 and the metal disk 25 when the latter is in the position shown in Fig. 3. On the plunger 8 is a flange 27, which actuates the disk 26 into its upper or closing position when the plunger is lifted while the circuit is opened upon the dropping of the plunger 8 by the simultaneous fall of this disk 25 by its own weight. A weight member 28 may be attached to the top of the plunger to insure the positive dropping of the plunger.

Mounted on the carriage 5, adjacent to the plunger, is a pivoted trackway or plate 30, which is hinged about the axis 31 to a box-like structure 32 mounted on the carriage. One side of this structure 32 is formed at an angle to the horizontal to provide a second trackway 33 for the roller 9 on the plunger for the purpose now to be described.

When the door is closed the plunger rests at one end, as indicated at 34, of the horizontal track 30, as seen in Fig. 1. As the door is moved to the left the roller 9 rides off the end of this trackway and the plunger drops suddenly, allowing the disk 25 to also drop and break the circuit. This action is effected during first travel of the door in opening. Upon the return movement of the door the beveled side 35 of the roller 9 on the plunger engages over the inclined track 33 and rolls up this trackway, lifting the pivoted power trackway 30 with it, as shown in Fig. 3, until it reaches the flat end portion 36 of the track 33, which is beyond the end of the pivoted track 30. The latter is thus allowed to return to its horizontal position and the roller rides over this horizontal trackway until it drops off on the next opening movement of the door.

The present switch mechanism gives an extremely quick switch opening, is simple in construction, and because of the rotation of the plunger 8, effected by the engagement of the beveled roller 9 on the edges of the trackways, the switch fingers 19 and 20 contact at different points on the disk 25 at every closing of the switch so that the wear on the

switch elements proper is distributed over the entire surface of a relatively large metal disk. It will be obvious that the plunger 8 in its vertical reciprocation will be caused to rotate through the engagement of the roller 9 with the track-way and consequently the cylindrical disc 26 will be rotated. This rotation presents the contact disc 25 at different positions and thus the wear thereon will be considerably reduced over the present types of switch mechanisms which have the contacts thereof engaged always at the same position.

We therefore particularly point out and distinctly claim as our invention:—

1. A switch mechanism comprising a hollow casing, contact members carried therein, a reciprocable plunger carried in said casing, a disk mounted on said plunger and adapted to engage said contact members, and means exteriorly of the casing for actuating said plunger, said means being movable transversely of the axis of said plunger and adapted to impart both rotary and reciprocatory movement to the plunger and disk.
2. A switch mechanism comprising fixed contact members, a reciprocable plunger, a metallic disk rotatably mounted on said plunger, and means movable transversely of the axis of the plunger for imparting simultaneously both reciprocatory and rotary movement to said plunger.
3. A switch mechanism comprising a hollow casing, contact members carried therein, a vertically reciprocable plunger carried

in said casing, a metallic disk mounted on said plunger, and movable means adapted to raise the plunger to engage said disk with said contact members, said means being also adapted to rotate said plunger and said plunger being adapted to drop downwardly by its own weight when not engaged by said means.

4. A switch mechanism comprising a casing, contact members carried therein, a vertically reciprocable plunger carried in said casing, a metallic disk mounted on said plunger, a roller carried on the lower end of said plunger, and sliding means consisting of an inclined trackway adapted to engage said roller to raise the plunger and engage said disk with said contact members, said roller imparting a rotary movement to said plunger during its engagement with said trackway.

5. In combination with a vertically reciprocable plunger having a roller at its lower end, of a horizontally sliding member consisting of an inclined plate adapted to engage said roller and raise said plunger when said member is moved in one direction, and of a pivoted trackway co-operating with said inclined trackway to hold said plunger in raised position for a part of its horizontal travel when said member is moved in the opposite direction.

Signed by us, this 20th day of February, 1923.

THOMAS E. GRIFFITH.
LEE L. DODDS.
